FUSE DEVICE

William O. Schultz, South Milwaukee, Wis., assignor to Line Material Company, South Milwaukee, Wis., a corporation of Delaware

Application October 10, 1941, Serial No. 414,444

23 Claims.

(Cl. 200—114)

This invention relates to fuse devices. Objects of this invention are to increase the rupturing capacity of fuse devices, to lessen the internal pressure generated by the violent explosions on large overloads, and to thereby increase the safety against bursting of the fuse tube, and to provide for a quicker and more positive interruption of the circuit within the fuse tube on either small or large overloads.

A further object is to provide for the positive detaching of a drop-out fuse tube from one of the stationary terminals to thereby insure the positive removal of the fuse tube from its operative position between the terminals upon the occurrence of an overload after first having interrupted the circuit within the fuse tube in a positive and quick manner.

Further objects are to provide fuse link extracting means for expulsion fuse devices which are so constructed that they insure a quick interruption of the circuit within the fuse tube upon overload and a positive withdrawal of a portion at least of the fuse link within the fuse tube, such fuse link extracting means upon light overloads having a positive spring action to withdraw the fuse link and upon heavy overloads having this action augmented by the gas pressure acting upon the fuse link extracting means.

In drop-out fuse devices of the expulsion type in which the fuse tube is mounted on a pivot or hinge, damage to parts of the device sometimes occurs on large overloads. When a violent overload occurs, the expulsion action of the fuse tube is great and there is a violent upward recoil followed by a violent downward rebound which frequently results in injury to the terminals and especially to the lower hinge which supports these drop-out fuse tubes.

Further objects of this invention are to provide a novel construction of drop-out fuse device of the expulsion type in which the fuse tube is allowed to discharge from both ends to thereby more or less equalize the mechanical thrust exerted on the fuse tube to thereby lessen both the upward recoil and the downward rebound with consequent increase in safety of the parts of the device and lessening of strain imposed on the entire apparatus.

Further objects are to simplify the construction of drop-out fuse devices, to lessen the cost thereof, and to accomplish both of these objects while securing the advantageous features hereinabove enumerated.

Embodiments of the invention are shown in the accompanying drawings, in which:

Figure 1 is a vertical view, with parts in section and broken away, showing the fuse in its operative position.

Figure 2 is a view of the underside of the upper lever at the upper end of the fuse tube, such

view being taken along the line 2—2 of Figure 5.

Figure 3 is a sectional view on the line 3—3 of Figure 1.

Figure 4 is a view of the upper end of the fuse tube after it has been refused and while it is removed from the stationary supporting means.

Figure 5 shows the construction of Figure 1 at an intermediate portion in its operation with a part of the upper stationary terminal in section.

Figure 6 is a view of the lower end of the device shown in Figure 1 after the fuse tube has rocked to its lowest position with a part of the lower stationary terminal in section.

Figure 7 is a view of a further form of the invention, with parts broken away and in section.

Figure 8 shows a further form of the invention, with parts broken away and in section.

Figure 9 shows a further form of the invention in which the upper end of the fuse tube is closed and is provided with a rigid contact.

Figure 10 is a front view of the structure shown in Figure 9.

Referring to the drawings, particularly Figures 1 to 6, inclusive, where one form of the invention is shown, it will be seen that the drop-out fuse comprises a fuse tube 1 formed of insulating material which is provided with upper and lower terminal contact assemblies indicated generally at 2 and 3 which engage upper and lower stationary terminals 4 and 5. The stationary terminals are carried from any suitable insulating support such as the elongated insulator 6 which may in turn be supported by a bracket 7 clamped to the insulator intermediate its ends.

The upper stationary terminal 4 may be a hood like structure as shown in Figures 1, 3 and 5, or it may be an open structure as shown in Figure 7 hereinafter described.

40 This hood like member is provided with a transversely extending cam like latching lip 8 which projects downwardly interiorly thereof and is provided with a slanting outer face and a somewhat rounded inner face. The lower stationary terminal 5 consists of a pair of hook like portions as indicated which are adapted to receive trunnions 9 carried by the lower terminal assembly 3 of the drop-out fuse tube. This lower terminal assembly 3 is provided with a rounded portion 10 which prevents removal of the fuse tube from the lower stationary terminal 5 until the fuse tube has been rocked downwardly to approximately the position as shown in Figure 6, at which time it may be unhooked

55 from the lower pair of hook members constituting the lower terminal 5. If desired, the lower terminal assembly of the fuse tube may be provided with a hook like portion 11 which is adapted to receive the end of the switch stick so that the fuse tube may be lifted from the lower termi-

nal member 5 for refusing and may be replaced by means of the switch stick after it has been refused. The lower terminal 3 of the fuse tube 1 is provided with a thumb nut 12 threaded on a projecting stem rigid with the lower terminal assembly 3 of the fuse tube so that the flexible leader 13 of the fuse link may be clamped in place.

The upper terminal assembly of the fuse tube is provided with a sleeve or cap portion 14 which is equipped with an eyelet 15 for the reception of the switch stick so that the device may be rocked into or rocked out of operative position.

This upper portion 14 is provided with projecting ears 16 on which a biased lever 17 is pivotally mounted by means of the pintle pin 18. The lever 17 is spring urged upwardly by means of the spring 19, one end of the spring bearing against the portion 14 and the other end bearing against a transverse web integral with the lever 17, as shown most clearly in Figures 1 and 3. The upper terminal assembly 2 of the fuse tube is provided with a main lever 20 which is pivoted adjacent one end by means of the pintle pin 21 on the spring pressed lever 17. This end or outer end of the lever 20 is provided with a cam-shaped or interlocking latch portion 22 which normally engages behind the cam lip 8 of the upper stationary terminal 4 and thus holds the fuse tube in its operative position. The lever 20 at the portion where it extends over the upper member 14 of the fuse tube is provided with an internally threaded sleeve like boss 23 which receives the clamping nut 24. This clamping nut engages the buttonhead 25 of the fuse link.

If desired, the fuse link may have an upper leader portion 26 with the upper and lower leaders joined by means of the fusible section 27 and the strain wire 28, though, if desired and as will appear hereinafter, the fusible section may or may not have the strain wire associated with it and also may be located approximately centrally or adjacent the upper or lower end of the fuse link, as will appear hereinafter.

It is to be noted that the fuse link is threaded through an aperture in the lever 20 and its buttonhead clamped in place by means of the clamping plug or nut 24. It is threaded through the fuse tube and projects outwardly through the open end thereof and is secured in place by means of the lower thumb nut 12. The lower end of the fuse tube is permanently open and the upper end though closed under normal conditions, opens up when the fuse link is ruptured so as to give a free discharge passage for the gases from both ends of the fuse tube. Normally, however, the lever 20 effectively closes the upper end of the fuse tube 1. If desired, the lever 20 may be provided with flanges 29, as shown in Figure 2, extending around a greater or less extent of the enlarged or outer end of the lever to thereby at least partially surround the upper end of the fuse tube, thereby effectively protecting such upper end from the entrance of rain, snow or sleet.

It is to be noted from an inspection of Figures 1, 4 and 5, that the upper portion 14 is provided with a pair of stops 30 which engage extensions 31 of the lever 17 and act as stops to limit the rocking motion of the lever 17 when such lever is free to move under the influence of the spring 19, as will hereinafter appear. For example, when the device is refused, the stops 30 allow the levers 17 and 20 to move to the posi-

tion shown in Figure 4. When the fuse tube is rocked into operative position, the lever 20 has its outer end depressed by the cam latching lip 8 of the upper stationary terminal 4 and such outer end of the lever rides under this latching lip and interlocks with it, as shown in Figure 1, thus retaining the fuse tube in position. There is a slight rocking and sliding motion between the other end of the lever 20 and the upper end 10 of the fuse tube during this operation.

Assume that the device is in its operative position as shown in Figure 1 and that an overload occurs. Whether this overload is a small overload or a heavy overload, the device functions to quickly interrupt the circuit within the fuse tube when the fusible section 27 and the strain wire 28 are ruptured upon overload and the spring pressed lever 17 urges the lever 20 upwardly and thus causes the lever 20 to act as a fuse link extractor to insure the extraction of a portion at least of the fuse link from the fuse tube and to thus insure the wide separation of the severed end of the fuse tube. This separation occurs very quickly due to the fact that the lever 20 is spring urged upwardly through the medium of the lever 17 and makes a quick upward rocking motion even though the overload may be relatively small. In the event of a heavy overload, in addition to the action of the spring, there is 15 the effect of gas pressure acting on the end of the lever 20 to assist in the quick upward rocking motion of such lever. The stops 30 come into play for a second function in addition to that previously described in that they limit the upward motion of the lever 17 and thus prevent 20 such lever from acquiring a great amount of momentum even if the lever 20 is blown upwardly violently, as the stroke of the lever 17 is relatively restricted. A part of the energy imparted to the lever 20 in its upward travel is 25 utilized usefully not only to withdraw the upper portion of the fuse link but also to act in the capacity of a cam to rock about the upper stationary contact 4 and to thus cam or force the fuse tube 1 towards its outer detached positions 30 so that the fuse tube is positively driven to detached position through the normal action of the parts.

An intermediate position is shown in Figure 5 where the lever 20 is traveling upwardly and will soon arrive at the point where it acts against the upper contact 4 to force the upper end of the fuse tube away from the upper stationary contact, at the same time unhooking from beneath the latching lip 8. The fuse tube then drops to 35 the position shown in Figure 6.

It is to be noted on comparing Figures 1 and 5 that the pivot point 21 moves upwardly when the fuse link is ruptured and that the lever 20 swings about the pivot point 21. Consequently, 40 the fuse link is extracted more nearly in line with the fuse tube than if the pivot point 21 had been a pivot point fixed with reference to the fuse tube. Instead the pivot point 21 moves upwardly with reference to the fuse tube on rupture of the fuse link and an extensive throw or movement is permitted the lever 20 without sharply drawing the fuse link at an angle across the upper end of the fuse tube.

It may be readily removed by hooking the switch stick beneath the portion 11 of the lower terminal assembly 3 of the fuse tube and lifting the trunnions 9 from the hooks of the lower stationary terminal 5. Thereafter the device may be readily refused and may be replaced by means 45

of the switch stick so that the fuse tube hangs downwardly in a slanting manner as shown in Figure 6. Thereafter the switch stick is caused to engage the eyelet 15 of the upper portion of the fuse tube and the fuse tube is rocked back into operative position, the outer end of the lever 20 riding beneath the latching lip 8 of the upper stationary contact 4.

It is to be noted that even under violent explosion the fuse tube is substantially protected from excessive gas pressure as it is vented from both ends. The reactions from the blast of gases from opposite ends of the fuse tube are somewhat balanced against each other and this lessens the upward recoil of the fuse tube and also lessens the downward rebound and thereby materially lessens the strain imposed on the different parts of the apparatus.

It is to be noted also that during the initial portion of the rupturing of the circuit, that the upper end of the lever 20 substantially closes the fuse tube 1 for an instant and insures an an explosion action even under small overload. In addition to this, the upper lever 20 being spring biased upwardly by the spring biased auxiliary lever 17, acts as a fuse link extractor even under light overloads and thus insures quick separation of the severed end of the fuse link within the fuse tube. In actual operations of this device it has been found that the circuit is interrupted and the arc extinguished within the fuse tube under both heavy and light overloads prior to the time that contact is broken between the upper terminal assembly of the fuse tube and the upper stationary contact so that there is no arcing between these parts when the fuse tube drops outwardly to its inoperative position.

Any upward recoil that the device may have is resisted due to the fact that the trunnions 9 are hooked beneath the overhanging lips of the hook like lower terminal member 5 and the fuse tube cannot be detached from such lower stationary terminal until it has been rocked to its inoperative position. However, as stated, even the amount of recoil and the amount of rebound is very materially reduced by this construction.

In the form of the invention shown in Figure 7, the fuse tube is indicated at 32 and the upper and lower terminal assemblies of the fuse tube are indicated generally at 33 and 34. The upper and lower stationary terminals are indicated respectively at 35 and 36.

In this form of the invention the tube is provided with an upper apertured part 37 and an integral eyelet 38. This construction is provided with an auxiliary spring pressed lever 39 which is pivoted to lips formed on the member 37 and is urged upwardly by means of the spring 40. The total upward motion of the lever 39 when it is free to move upwardly is limited by means of stops 41 which are adapted to be engaged by projections 42 integral with the lever 39. The outer end of the lever 39 is pivoted as indicated at 43 to the main lever 44.

The main lever is provided with a cam like portion 45 which interlocks behind the cam like latching lip 46 of the upper stationary contact 35. This upper stationary contact 35 is shown as unhooded or open, but it is to be understood that either an open or the hooded type can be used interchangeably with any form of the invention.

The lever 44 extends across the open upper

end of the fuse tube and is apertured so that the buttonheaded fuse link may be threaded through the lever and through the fuse tube 32. The buttonhead 47 of the fuse link bears directly against the upper surface of the end of the lever 44.

The lower portion of the fuse tube is provided with an arm 48 which is integral with a sleeve 49 rigidly secured adjacent the lower portion of the fuse tube 32 and which projects outwardly from the fuse tube as indicated. It is bifurcated at its outer end and carries the pintle pin 50 whereby the fuse link extracting lever 51 is pivoted thereto.

The fuse link extracting lever 51 is provided with trunnions 52 which are received in the hook like portions of the lower stationary terminal 36. This lever 51 is provided with the rounded portion 53 cooperating with the lower stationary terminal to prevent removal of the fuse tube therefrom until the fuse tube has dropped downwardly to inoperative position. The lever 51 is provided with a thumb nut 54 threaded on a projecting threaded stem carried by the lever 51 for securing the lower leader portion 55 of the fuse link in place. The fuse link is provided with an upper leader portion 56 which extends downwardly from the buttonhead 47 and is joined to the lower leader portion 55 by means of the fusible section 57 and by means of the strain wire 58. As stated, the fusible section either with or without the strain wire may be located wherever desired along the length of the fuse link either in the middle or adjacent the upper or lower ends of the fuse tube.

The operation of this apparatus upon the occurrence of an overload is as follows: The upper main lever 44 when the fuse link is ruptured, acts as a fuse link extractor, being urged quickly upwardly by means of the spring biased auxiliary lever 39 and also by any gas pressure that may act on the lower portion of the end of the lever 44. This causes the lever 44 to rock about the pin 43 while the auxiliary lever 39 rocks about its pivot pin 59. The upward rocking of the lever 44 causes such lever to act against the stationary upper contact 35 to force the fuse tube outwardly towards its inoperative position. In addition to this action, the lower lever 51 acts in the capacity of a double-jointed hinge to further assist in the extraction of any remaining portion of the fuse link.

The upper lever 44 is also urged upwardly by gas pressure in addition to its upward urge due to the spring action hereinbefore described. Under violent overloads it will be seen that the pressure within the fuse tube is relieved at both ends of the fuse tube and the blasts from opposite ends of the fuse tube tend to balance each other, thereby reducing both the recoil and the rebound, the upward recoil being resisted by the overhanging hook like portions of the lower stationary terminal 36 which cannot become detached from the trunnions 52 of the fuse tube until the fuse tube has rocked downwardly to inoperative position.

In the event of a small overload, the circuit is quickly interrupted within the fuse tube due to the spring action of the upper main lever 44 which, as stated, is urged upwardly by the spring pressed auxiliary lever 39, and thus even under small overloads the circuit is quickly interrupted within the fuse tube.

Figure 8 shows a further form of the invention in which the fuse tube 60 is provided with upper

and lower terminal assemblies indicated generally at 61 and 62. Each of these assemblies includes a spring biased main lever for extracting the fuse link. The upper main lever 63 is biased upwardly by means of an auxiliary lever 64 biased by means of the spring 65 and pivoted as indicated at 66 to lips integral with the upper metal member 67 which is rigidly mounted on the upper end of the fuse tube.

The lever 64 is provided with a pair of arms 68 located on opposite sides of the lips of the member 67. These arms are provided so that they will engage stops 69 formed on the member 67 to thus allow limited motion of the lever 64 when such lever is free to move as hereinafter described. The outer end of the lever 64 is pivoted as indicated at 70 to the lever 63. The lever 63 is provided with a cam like latching portion 71 which interlocks with a downwardly projecting rib or latching lip 72 integral with the upper stationary contact 73.

The latching lip 72 is bevelled on its outer face to provide a cam surface to allow the cam portion 71 to ride beneath such lip when the fuse is rocked back to operative position, the spring 65 yielding slightly and the other end of the lever 63 rocking and sliding a slight amount at the upper end of the fuse tube. The stationary contact may be either an open type or a housed type, a housed type having been shown. The lever 63 extends over the open upper end of the fuse tube and is provided with a sleeve like internally threaded boss 74 within which the buttonhead 75 of the fuse link is positioned, the lever being apertured and the fuse link extending through the aperture and through the fuse tube 60 outwardly from its bottom end. The buttonhead 75 is clamped in position by means of the clamping nut or plug 76.

The lower terminal portion of the fuse tube includes a main lever 77 which is provided with trunnions 78 that fit within the overhanging hook-shaped arms of a lower stationary contact 79.

The lever 77 is also provided with a rounded rear portion 80 which prevents removal or detachment of the fuse tube from the lower contact until the fuse tube has rocked down to inoperative position. The lever 77 is provided with a thumb nut 81 screwed onto the threaded stem carried by the lever 77 and serves to clamp the lower portion of the leader 82 of the fuse link in place.

The fuse link is provided with a fusible section 83 and a strain wire 84 which joins the upper and lower flexible leaders of the fuse link. If desired, the strain wire may be omitted. The fusible section may be located at any point along the fuse link. For example, it may be located at the lower point as shown or may be located approximately centrally of the fuse tube, as in Figure 7 for instance, or may be located adjacent the upper end of the fuse tube, as in Figure 9 hereinafter described.

A metal sleeve 85 is rigidly attached adjacent the lower end of the fuse tube and is provided with a pair of ears 86 which are pivotally joined to the downwardly biased auxiliary lever 87 by means of the pintle pin 88. A spring 89 urges the lever 87 downwardly. The outer end of the lever 87 is pivotally joined to the main lever by means of the pintle pin 90. The inner end of the auxiliary lever 87 is provided with a pair of extensions 87' which engage stops 88' after lim-

ited motion of the lever 87 when such lever is free to move.

The lower lever 77 is provided with a switch stick receiving hooked member 91 and the upper member 67 rigidly carried by the fuse tube is provided with a switch stick receiving eyelet 92.

Assume that the device of Figure 8 is in the position shown, namely, in operative position, and that an overload occurs. When the overload occurs, both the upper lever 63 and the lower lever 77 act to extract the fuse link as each of them is spring urged outwardly away from the open end of the fuse tube and thus serve to quickly draw any remaining portions of the fuse link outwardly. In addition to this, it is to be noted that the gas pressure is vented from both ends of the fuse tube. The fuse tube has an expulsion action in addition to the fuse link extracting action hereinbefore described. The upper lever 63 initially extends over the upper open end of the fuse tube and thus assists in the expulsion action. However, the gas pressure quickly moves the upper lever upwardly and also, if desired, may assist in the downward motion of the lower lever, the amount of assistance given the lower lever by the gas pressure being proportioned to the amount the end of the lower lever overlaps the open lower end of the fuse tube. The upper lever 63 has a cam action against the outer face of the upper stationary contact 73 and serves to force the fuse tube outwardly to insure detaching of the upper terminal of the fuse tube from the upper stationary terminal.

After the circuit has been interrupted within the fuse tube, the fuse tube drops downwardly to its lowermost or inoperative position. It may be removed from the lower stationary contact 79 by lifting it upwardly and outwardly with a switch stick, the switch stick engaging the member 91.

After the fuse tube has been removed from the lower stationary contact, it may be refused and may be again lifted up by means of the switch stick and the trunnions 78 placed within the hooks of the lower stationary terminal 79. Thereafter the operator engages the eyelet 92 with the switch stick and rocks the fuse tube back into its operative position, the latching cam like member 71 riding beneath the latching cam like lip 72. The lever 64 rocks downwardly against the action of the spring 65 a light amount and the end of the lever 63 immediately over the upper end of the fuse tube slides and rocks slightly with reference to the upper end of the fuse tube. In addition to this action, during the final latching motion of the fuse tube the lower terminal assembly of the fuse tube can yield slightly to thus facilitate the latching operation.

It is to be distinctly understood that any of the parts of one form of the invention may be used with any of the other parts of any other form of the invention wherever desirable or applicable. For example, the buttonhead of the fuse link may be clamped in place in any of the forms or the buttonhead may merely bear against the upper end of the upper lever in any of the forms. In addition to this, any type of upper contact whether hooded or open can be used with any of the several forms of the invention and other interchanges of parts, as stated hereinabove, may be made wherever desired.

In the form of the invention shown in Figure 1 the spring biased main lever supported by the auxiliary lever is shown adjacent the upper end of the fuse tube and the lower terminal por-

tion of the fuse tube is shown as a rigid structure. In Figure 7 the lower terminal of the fuse tube may be the double link construction and the upper terminal of the fuse tube may be the spring biased main lever supported by the auxiliary lever. In the form of the invention shown in Figure 8 the spring biased main lever supported by the auxiliary lever is shown for both of the upper and lower terminals of the fuse tube.

The invention also contemplates the provision of a rigid upper terminal for the fuse tube and the spring biased main lever supported by an auxiliary lever for the lower terminal of the fuse tube. This form of the invention is shown in Figures 9 and 10.

In this form of the invention the fuse tube is indicated by the reference character 93. It is provided with a closure cap 94 which is screw threaded on the upper threaded tubular extension 95 of the upper terminal member 96 of the fuse tube and clamps the buttonhead 97 of the fuse link thereto. The fuse link may be provided with a fusible section 98 adjacent its upper end and with a flexible leader 99 extending downwardly therefrom through the open lower end of the fuse tube. If desired, a strain wire may be used in connection with the fusible section 98, as previously described.

The upper terminal 96 of the fuse tube includes the switch stick receiving eyelet portion 100 and the cam like latching portion 101. This cam like latching portion may be provided with an outwardly extending beveled portion 102. The latching or cam like portion 101 is adapted to latch beneath the latching lip 103 of the upper stationary contact 104. The upper stationary contact 104 is provided with a downwardly slanting cam like surface 105 to assist in guiding the portion 101 into interlocking position, the lower terminal structure yielding to accommodate this action as will hereinafter appear. The upper stationary contact may be provided with outwardly flaring side walls as indicated at 106 and shown most clearly in Figure 10 to assist in guiding the upper terminal of the fuse tube into position.

If desired, in each form of the invention the upper contact may be provided with a downwardly extending portion which acts as a stop to limit the inward rocking motion of the fuse tube assembly when it is being rocked back into operative position after refusing.

The lower terminal of the fuse tube is indicated generally by the reference character 107 and may comprise the spring pressed auxiliary lever 108 pivoted on the pivot pin 109 to lips 110 integral with the lower sleeve like metal member 111 rigidly secured adjacent the lower end of the fuse tube.

The lever 108 may be channel-shaped if desired and is urged downwardly by means of the spring 112. It is provided with a pair of arms 113 located on opposite sides of the lips 110 and constitute extensions adapted to be limited in their motion by means of the stops 114 integral with the member 111. The outer end of the auxiliary lever 108 is pivotally connected to the main lever 115 by means of the pintle pin 116. If desired, the pintle pin 116 may have a loose fit with the lever 115. The lever 115 carries the thumb nut 117 screw threaded on a threaded stem 118 carried by the lever 115 and acting as a clamp to clamp the lower end of the flexible leader 99 of the fuse link. If desired, the lever

115 may be slightly cut out at its free end so as to provide a pair of lips 119 which partially surround the lower end of the fuse tube.

5 The main lever or fuse extracting lever 115 is provided with trunnions 120 which are normally engaged by the hooked portions 121 of the lower stationary terminal member 122. The main lever 115 may be provided with a curved rear extension 123 cooperating with the curved portion 124 of the lower stationary terminal 122 to prevent inadvertent detachment of the trunnions 120 from the hooks of the lower stationary terminal. The curved portion 123 of the main lever 115 may also serve to receive the switch stick when the fuse tube assembly is being lifted into and out of engagement with the lower stationary terminal.

20 Assume that the device of Figures 9 and 10 is in operative position and an overload occurs. The downwardly biased lever 115 quickly extracts any remaining portion of the fuse link and thus assists in clearing the device in addition to the expulsion action. The main lever 115 is spring biased downwardly by means of the auxiliary lever 108 and thus quickly moves downwardly.

25 The downward motion of the spring biased lever 115 lowers the fuse tube and causes the cam like latching member 101 of the upper terminal of the fuse tube to become detached from the upper stationary terminal 104 and the fuse tube then rocks downwardly to its inoperative position. However, the circuit is interrupted within the fuse tube prior to the time the upper terminal of the fuse tube breaks contact with the upper stationary terminal.

30 The device may be lifted from the lower stationary terminal by means of a switch stick through the medium of the portion 123 thereof and may be refused. After refusing it is again 35 lifted into position by means of the switch stick and its trunnions 120 fitted within the hook portions of the lower stationary terminal. The switch stick is then placed in engagement with the eyelet portion 100 of the upper terminal of the fuse tube and the fuse tube is rocked into operative position. If desired, the switch stick may in 40 any of the forms of the invention shown herein be used merely to push the fuse tube into its operative position after once having been used to place the lower trunnions of the fuse tube in 45 engagement with the lower stationary terminal.

50 In this last described form of the invention shown in Figures 9 and 10 the advantage of simultaneous relief of pressure at both ends of the fuse tube as in the other forms of the invention is not obtained. However, this form of the invention shows the spring biased fuse link extracting lever and the auxiliary spring urged lever cooperating therewith and located at the lower portion of a fuse tube.

55 It is to be noted in connection with this last described form of the invention that when the refused device is rocked back into operative position, there is a yield in the lower terminal 107 of the fuse tube and thus the portion 101 of the upper terminal of the fuse tube is permitted to ride beneath the latching lip 103 of the upper stationary terminal.

60 In all forms of the invention it will be seen that the main lever constitutes a combined fuse link extracting and latching lever and that this main lever is biased towards fuse link extracting and unlatching motion by means of the biased or spring urged auxiliary lever by which it 65 is pivotally carried.

A few of the many forms that the invention may take have been illustrated and it will be seen that the combined fuse link extracting and latching lever may be positioned at either end of the fuse tube with the other end of the fuse tube provided with any suitable type of terminal means, and with the fuse tube either open at both ends or closed at one end, and also it will be seen that combined fuse link extracting and latching levers may be positioned at both ends of the fuse tube.

It will be seen further that the combined fuse link extracting and latching lever may be made relatively light and may have a very quick fuse link extracting motion prior to the motion of other and more massive parts of the apparatus and thus may have a very quick fuse link extracting action which may or may not be assisted by the gas pressure generated within the fuse tube itself, depending on the severity of the explosion resulting from rupture of the fuse link.

In all forms of the invention it will be seen that a very quick fuse link extracting action takes place without requiring motion of all parts of the fuse tube assembly and instead requiring motion of a spring biased, relatively small portion of the structure. This quick clearing of the device is also assisted by the expulsion action in all forms of the invention. This quick break insures a quick clearing of the circuit within the fuse tube itself prior to the outward rocking motion of the drop-out fuse tube. The device is thus enabled to have a positive operation even for small overloads and is also enabled to handle larger overloads because of its ability to quickly clear the circuit within the fuse tube itself.

With particular reference to the forms of the invention illustrated by Figures 1 to 8, it is to be noted that novel forms of drop-out fuse devices have been shown which have the above recited advantages and also have the advantage of being able to handle very much larger overloads than heretofore as the device is so constructed that the relief of pressure occurs simultaneously at both ends of the fuse tube and thus the danger of bursting is materially reduced. Also there is a material lessening of both the recoil and the rebound and thus there is very much less strain put on the different portions of the apparatus.

In addition to these advantages, for the forms of the invention illustrated by Figures 1 to 8, there is the further advantage that the gas pressure acts on the fuse link extracting lever and assists further in quick fuse link extraction. Further, for these forms of the invention, the fuse link extracting lever assists in insuring the drop-out action of the fuse tube thus making these devices more positive in their drop-out action. However, in all forms of the invention it is to be noted that the fuse tube is biased towards drop-out motion.

It is to be noted also that although the novel fuse devices hereinabove described have the advantageous features discussed, nevertheless they are relatively simple in their construction.

Although this invention has been described in considerable detail, it is to be understood that such description is intended as illustrative rather than limiting, as the invention may be variously embodied and is to be interpreted as claimed.

I claim:

1. A drop-out fuse device comprising a support, a rigid upper terminal and a lower terminal, an expulsion fuse tube open at both ends

and movably supported from said support and biased towards motion away from one of said terminals, a fuse link within said fuse tube normally electrically connecting said terminals, and 5 a combined fuse link extracting and latching member biased towards fuse link extracting and unlatching motion and towards engagement with said upper stationary terminal and normally restrained by said fuse link and normally holding said fuse tube against drop-out motion, said combined fuse link extracting and latching member extending directly over at least a part of the open end of said fuse tube, whereby upon rupture of said fuse link gas pressure will assist in the fuse link extracting and unlatching motion of said combined fuse link extracting and latching member.

10 2. A drop-out fuse device comprising a support, upper and lower stationary terminals, an expulsion fuse tube having an open lower end and supported from said support, a fuse link within said fuse tube normally electrically connecting said terminals, a fuse link extracting lever normally restrained by said fuse link, and 15 a spring biased auxiliary lever acting upon said fuse link extracting lever and urging said fuse link extracting lever towards fuse link extracting motion, said fuse tube having a rigid upper terminal and said upper stationary terminal being rigid and normally interlocking with the rigid upper terminal of said fuse tube.

20 3. A fuse device comprising a support, a pair of terminals, an expulsion fuse tube open at both ends and supported from said support, a fuse link within said fuse tube normally electrically connecting said terminals, a fuse link extracting lever normally restrained by said fuse link, and 25 a biased auxiliary lever pivotally joined to said fuse link extracting lever and urging said fuse link extracting lever towards fuse link extraction motion.

30 4. An expulsion fuse device comprising a support, a pair of terminals, an expulsion fuse tube open at both ends and supported from said support, a fuse link within said fuse tube normally electrically connecting said terminals, a fuse link extracting lever having one end attached to said fuse link, and a spring biased auxiliary lever pivotally supporting said fuse link extracting lever and urging said fuse link extracting lever towards fuse link extracting motion.

35 5. A fuse device comprising a support, a pair of terminals, an expulsion fuse tube open at both ends and supported from said support, a fuse link within said fuse tube normally electrically connecting said terminals, a fuse link extracting lever having one end attached to said fuse link, and a spring biased auxiliary lever pivotally supporting said fuse link extracting lever and urging said fuse link extracting lever towards fuse link extracting motion.

40 6. A fuse device comprising a support, a pair of terminals, an expulsion fuse tube open at both ends and supported from said support, a fuse link within said fuse tube normally electrically connecting said terminals, a fuse link extracting lever having one end attached to said fuse link, and a spring biased auxiliary lever pivotally supporting said fuse link extracting lever and urging said fuse link extracting lever towards fuse link extracting motion.

45 7. A fuse device comprising a support, a pair of terminals, an expulsion fuse tube open at both ends and supported from said support, a fuse link within said fuse tube normally electrically connecting said terminals, a fuse link extracting lever having one end attached to said fuse link, and a spring biased auxiliary lever pivotally supporting said fuse link extracting lever and urging said fuse link extracting lever towards fuse link extracting motion.

50 8. A fuse device comprising a support, a pair of terminals, an expulsion fuse tube open at both ends and supported from said support, a fuse link within said fuse tube normally electrically connecting said terminals, a fuse link extracting lever having one end attached to said fuse link, and a spring biased auxiliary lever pivotally supporting said fuse link extracting lever and urging said fuse link extracting lever towards fuse link extracting motion.

55 9. A fuse device comprising a support, a pair of terminals, an expulsion fuse tube open at both ends and supported from said support, a fuse link within said fuse tube normally electrically connecting said terminals, a fuse link extracting lever having one end attached to said fuse link, and a spring biased auxiliary lever pivotally supporting said fuse link extracting lever and urging said fuse link extracting lever towards fuse link extracting motion.

60 10. A fuse device comprising a support, a pair of terminals, an expulsion fuse tube open at both ends and supported from said support, a fuse link within said fuse tube normally electrically connecting said terminals, a fuse link extracting lever having one end attached to said fuse link, and a spring biased auxiliary lever pivotally supporting said fuse link extracting lever and urging said fuse link extracting lever towards fuse link extracting motion.

65 11. A fuse device comprising a support, a pair of terminals, an expulsion fuse tube open at both ends and supported from said support, a fuse link within said fuse tube normally electrically connecting said terminals, a fuse link extracting lever having one end attached to said fuse link, and a spring biased auxiliary lever pivotally supporting said fuse link extracting lever and urging said fuse link extracting lever towards fuse link extracting motion, whereby upon

rupture of said fuse link said fuse link extracting lever will execute fuse link extracting motion by the force exerted by said spring means and by any gas pressure that may be generated within said fuse tube.

7. A drop-out fuse device comprising a support, a pair of terminals, an expulsion fuse tube open at both ends and pivotally supported from said support and biased towards motion away from one of said terminals, a fuse link within said fuse tube normally electrically connecting said terminals, a fuse link extracting lever connected to said fuse link and normally restrained by said fuse link, and a spring biased auxiliary lever pivoted with reference to said fuse tube and pivoted to said fuse link extracting lever and urging said fuse link extracting lever towards fuse link extracting motion, said fuse tube being normally held in operative position and being released when said fuse link extracting lever executes fuse link extracting motion.

8. A drop-out fuse device comprising a support, a pair of terminals, an expulsion fuse tube open at both ends and movably supported from said support and biased towards motion away from one of said terminals, a fuse link within said fuse tube normally electrically connecting said terminals, a combined fuse link extracting and latching lever normally restrained by said fuse link and interlocking with one of said terminals, and a biased auxiliary lever pivotally supporting said combined fuse link extracting and latching lever and urging said combined fuse link extracting and latching lever towards fuse link extracting and unlatching motion.

9. A drop-out fuse device comprising a support, a pair of terminals, an expulsion fuse tube open at both ends and movably supported from said support and biased towards motion away from one of said terminals, a fuse link within said fuse tube normally electrically connecting said terminals, a combined fuse link extracting and latching lever normally restrained by said fuse link and interlocking with one of said terminals, and a biased auxiliary lever pivotally supporting said combined fuse link extracting and latching lever and urging said combined fuse link extracting and latching lever towards fuse link extracting and unlatching motion, said combined fuse link extracting and latching lever releasing itself from the terminal to which it is normally latched when released by said fuse link.

10. A drop-out fuse device comprising a support having a first and a second stationary terminal, an expulsion fuse tube open at both ends and having a terminal adjacent each end thereof, a fuse link within said fuse tube normally electrically connecting the terminals of said fuse tube, one of said fuse tube terminals being pivotally supported from said second stationary terminal, the other of the terminals of said fuse tube including a combined fuse link extracting and latching lever normally interlocking with said first stationary terminal and normally restrained by said fuse link, and a biased auxiliary lever pivotally supporting said combined fuse link extracting and latching lever, and urging said combined fuse link extracting and latching lever towards fuse link extracting and unlatching motion.

11. A drop-out fuse device comprising a support having a pair of stationary terminals, an expulsion fuse tube open at both ends and having at least one terminal adjacent one end thereof and being pivotally supported adjacent the other

end thereof from said support, a fuse link within said fuse tube normally electrically connecting said stationary terminals, the terminal of said fuse tube including a combined fuse link extracting and latching lever normally interlocking with one of said stationary terminals and normally restrained by said fuse link, and a spring pressed auxiliary lever pivotally supporting and biasing said combined fuse link extracting and latching lever towards fuse link extracting and unlatching motion, said combined fuse link extracting and latching lever normally closing one end of said fuse tube.

12. A drop-out fuse device comprising a support having a pair of stationary terminals, an expulsion fuse tube open at both ends and having at least one terminal adjacent one end thereof and being pivotally supported adjacent the other end thereof from said support, a fuse link within said fuse tube normally electrically connecting said stationary terminals, the terminal of said fuse tube including a combined fuse link extracting and latching lever normally interlocking with one of said stationary terminals and normally restrained by said fuse link, a spring pressed auxiliary lever pivotally supporting and biasing said combined fuse link extracting and latching lever towards fuse link extracting and unlatching motion, said combined fuse link extracting and latching lever normally closing one end of said fuse tube, and stop means for limiting the motion of said spring pressed auxiliary lever.

13. A drop-out fuse device comprising a support having a pair of stationary terminals, an expulsion fuse tube open at both ends and having at least one terminal adjacent one end thereof and being pivotally supported adjacent the other end thereof from said support, a fuse link within said fuse tube normally electrically connecting said stationary terminals, the terminal of said fuse tube including a combined fuse link extracting and latching lever normally interlocking with one of said stationary terminals and normally restrained by said fuse link, a spring pressed auxiliary lever pivotally supporting and biasing said combined fuse link extracting and latching lever towards fuse link extracting and unlatching motion, said combined fuse link extracting and latching lever normally closing one end of said fuse tube, and stop means for limiting the motion of said spring pressed auxiliary lever, the fuse link extracting and unlatching motion of said combined fuse link extracting and latching lever being assisted by gas pressure generated upon rupture of said fuse link.

14. A drop-out fuse device comprising a support having a first and a second stationary terminal, an expulsion fuse tube open at both ends and having a first and a second terminal adjacent the respective ends of the fuse tube, a fuse link within said fuse tube normally electrically connecting the first and second terminals of said fuse tube, the second terminal of said fuse tube including fuse link extracting means and being pivotally supported from said second stationary terminal, the first terminal of said fuse tube including a combined fuse link extracting and latching lever normally interlocking with said first stationary terminal and normally restrained by said fuse link and being spring urged towards fuse link extracting and unlatching motion.

15. A drop-out fuse device comprising a support having a first and a second stationary terminal, an expulsion fuse tube open at both ends and having a first and a second terminal adja-

cent the respective ends of the fuse tube, a fuse link within said fuse tube normally electrically connecting the first and second terminals of said fuse tube, the second terminal of said fuse tube including fuse link extracting means and being pivotally supported from said second stationary terminal, the first terminal of said fuse tube including a combined fuse link extracting and latching lever normally interlocking with said first stationary terminal and normally restrained by said fuse link, and a biased auxiliary lever pivotally supporting said combined fuse link extracting and latching lever and urging said combined fuse link extracting and latching lever towards fuse link extracting and unlatching motion.

16. A drop-out fuse device comprising a support, a pair of terminals, an expulsion fuse tube movably supported from said support for motion away from one of said terminals, a fuse link within said fuse tube normally electrically connecting said terminals, and a fuse link extracting lever, and spring means urging said lever towards fuse link extracting motion, said fuse link extracting lever being normally restrained by said fuse link and cooperating with one of said terminals and urging said fuse tube away from said terminal when said fuse link extracting lever executes fuse link extracting motion.

17. A drop-out fuse device comprising a support, a pair of terminals, an expulsion fuse tube movably supported from said support for motion away from one of said terminals, a fuse link within said fuse tube normally electrically connecting said terminals, and a fuse link extracting lever, and spring means urging said lever towards fuse link extracting motion, said fuse link extracting lever being normally restrained by said fuse link and cooperating with one of said terminals and urging said fuse tube away from said terminal when said fuse link extracting lever executes fuse link extracting motion, said fuse link extracting lever being carried by said fuse tube and moving bodily with said fuse tube away from said terminal when said fuse tube moves to drop-out position.

18. A drop-out fuse device comprising a support, a first and a second terminal, an open-ended expulsion fuse tube movably supported from said support for motion away from said first contact, a fuse link within said fuse tube normally electrically connecting said contacts, and a fuse link extracting lever extending across the open end of said fuse tube and spring urged towards fuse link extracting motion and normally restrained by said fuse link, the motion of said fuse link extracting lever being assisted by gas pressure upon rupture of said fuse link, said fuse link extracting lever when executing fuse link extracting motion cooperating with said first terminal to throw said fuse tube towards drop-out position and bodily moving with said fuse tube out of contact with said first stationary contact.

19. A drop-out fuse device comprising a support, an upper and a lower contact carried by said support, a drop-out fuse tube pivoted on said lower contact, a fuse link within said fuse tube normally electrically connecting said contacts, and a fuse link extracting lever pivotally supported from said fuse tube and biased for motion upwardly from the upper end of said fuse tube and normally restrained by said fuse link, said fuse link extracting lever having a rocking cam action with respect to said upper contact

to throw said fuse tube towards drop-out position upon rupture of said fuse link.

20. A drop-out fuse device comprising a support, an upper and a lower contact carried by said support, a drop-out fuse tube pivoted on said lower contact, a fuse link within said fuse tube normally electrically connecting said contacts, and a combined fuse link extracting and latching lever pivotally supported from said fuse tube and normally interlocking with said upper contact and spring urged upwardly from the upper end of said fuse tube, said lever being normally restrained by said fuse link and having a rocking cam action with respect to said upper contact to throw said fuse tube towards drop-out position upon rupture of said fuse link.

21. A drop-out fuse device comprising a support, a pair of terminals, an open-ended expulsion fuse tube movably supported from said support and biased towards motion away from one of said terminals, a fuse link within said fuse tube normally electrically connecting said terminals, a combined fuse link extracting and latching lever normally restrained by said fuse link and interlocking with one of said terminals, and a biased auxiliary lever pivotally supporting said combined fuse link extracting and latching lever and urging said combined fuse link extracting and latching lever towards fuse link extracting and unlatching motion, said combined fuse link extracting and latching lever releasing itself from the terminal to which it is normally latched when released by said fuse link and having a rocking cam action with respect to such terminal to throw said fuse tube towards drop-out position.

22. A fuse device comprising a support, a pair of terminals, an expulsion fuse tube open at both ends and supported from said support, a fuse link within said fuse tube normally electrically connecting said terminals, a fuse link extracting lever extending directly across an open end of said fuse tube and normally restrained by said fuse link, said fuse link extending through said fuse link extracting lever and having an enlarged head bearing against the outer side of said fuse link extracting lever, and spring means carried by said fuse tube urging said fuse link extracting lever towards fuse link extracting motion, whereby upon rupture of said fuse link said fuse link extracting lever will execute fuse link extracting motion by the force exerted by said spring means and by any gas pressure that may be generated within said fuse tube.

23. A fuse device comprising a support, a pair of terminals, an expulsion fuse tube open at both ends and supported from said support, a fuse link within said fuse tube normally electrically connecting said terminals, a fuse link extracting lever extending directly across an open end of said fuse tube and normally restrained by said fuse link, said fuse link having an enlarged head, means carried by said fuse link extracting lever for clamping said enlarged head directly to said fuse link extracting lever, and spring means carried by said fuse tube urging said fuse link extracting lever towards fuse link extracting motion, whereby upon rupture of said fuse link said fuse link extracting lever will execute fuse link extracting motion by the force exerted by said spring means and by any gas pressure that may be generated within said fuse tube.

WILLIAM O. SCHULTZ.
